PHYSICAL CONDITIONING DEVICE FOR FACIAL MUSCLES

Jack La Lanne, Hollywood, Calif., assignor to La Lanne
Incorporated, Hollywood, Calif.

Filed Dec. 29, 1960, Ser. No. 63,382

Term of patent 14 years

(Cl. D34—5)

Fig. 1.

Fig. 2.

Fig. 3.

Fig. 4.

FIG. 1 is a vertical elevational view, viewed from either the front or rear, of a physical conditioning device for facial muscles showing my new design.

FIG. 2 is a vertical elevational view, viewed from either side of the design shown in FIG. 1.

FIG. 3 is an end view of one end thereof.

FIG. 4 is an elevational view of an opposite end thereof.

I claim:

The ornamental design for a physical conditioning device for facial muscles, as shown and described.
